UNITED STATES PATENT OFFICE.

HUMPHREY EVANS, OF MILWAUKEE, WISCONSIN, ASSIGNOR TO HOLEPROOF HOSIERY CO., OF MILWAUKEE, WISCONSIN, A CORPORATION OF WISCONSIN.

KNITTING MACHINE.

Application filed October 23, 1922. Serial No. 596,266.

This invention relates more particularly to circular knitting machines having rotary needle cylinders.

Its main objects are to produce seamless tubular knitted articles with tapered reinforcements of various designs having curved, straight or stepped sides, such as pointed or tapered high splice heel reinforcements of stockings; to adapt circular knitting machines of a standard or well known type to produce such reinforcements; and generally to improve the construction and operation of mechanism for knitting seamless tubular hosiery with reinforcements of various designs.

It consists in the construction, arrangement and combination of parts as herein-after particularly described and pointed out in the appended claims.

20 In the accompanying drawing like characters designate the same parts in the several figures.

Figure 1 is a side elevation and vertical section of parts of a circular knitting machine embodying the invention; Fig. 2 is a rear elevation as viewed from the left relative to Fig. 1, of the splicing yarn guide operating mechanism; Fig. 3 is a plan view of the mechanism shown in Fig. 2, the supporting bracket being shown in horizontal section on the line 3-3, Fig. 2; and Figs. 4, 5, 6 and 7 are diagrams illustrating some of the numerous designs of high splice heel reinforcements which the machine is adapted to produce.

Referring to Fig. 1, 1 is the rotary needle cylinder of a well known kind of circular knitting machine, such as a Scott and Williams machine. It is provided as usual in this type of machines, with needles 2.

40 A sinker ring 3, provided with the usual sinkers of web holders 4, is mounted on and rotatable with the upper end of the needle cylinder.

45 A latch guard ring 6 is pivotally connected by a radially slotted and arched extension 7 on the rear side thereof with a post or standard 8, rising from a stationary bed 9, on which is rotatably mounted the needle cylinder 1, with a bevel gear 10 through which it is actuated by the usual or any suitable mechanism (not shown).

50 A yarn guide 12, pivoted on a cross pin 13 in the arched extension 7 of the latch guard ring, is movable at its inner and

lower end upward and downward out of and into operative position for directing splicing yarn to the needles 2. In its lower operative position, the yarn guide rests as shown, on a throat plate 14, attached to the latch guard 60 ring 6 and spanning the radial slot therein.

A spring 15 tends to swing the inner end of the yarn guide 12 downward, and to hold it in operative position on the throat plate 14.

65 The machine is provided, as usual in machines of this class, with a pattern drum or wheel 17, which is located below the yarn guide 12 and the bed 9 and is driven by the usual or any suitable actuating connections 70 (not shown).

70 A thrust bar 19, supported and guided by combs or bearings 20 and 21 between the yarn guide and pattern drum, is adapted by engagement with cams 22 and 23 on the pattern drum, to shift the yarn guide upward and hold it out of operative position during certain periods in the operation of the machine, as in knitting the toes, legs 80 and heels of stockings.

80 The construction and operation of the parts of the machine hereinbefore mentioned being well understood by those familiar with the art to which this invention pertains, need not be more particularly described.

85 For the purposes of the present invention, the machine is provided with splicing mechanism or means for supplying splicing yarn with the main yarn to the needles in knitting seamless tubular articles, such as hosiery, in successive partial courses of various lengths, to produce reinforcements, such as high splice heels of various designs, as illustrated for example, in Figs. 4 to 7 inclusive.

90 As shown in Figs. 1, 2 and 3, such mechanism or means comprises a cam 25, splined and shiftable axially on a shaft 26, with which it is rotatable at the same rate of speed as the needle cylinder. The shaft 26 is supported by bearings in a bracket 27, which is attached to the needle cylinder bed 9. The cam 25, which is generally of cylindrical shape, is formed in one side with a longitudinal depression 28, of tapering form 105 or varying width.

95 A lever 30, fulcrumed on a pin 31 parallel with the shaft 26, is provided at one end with a roller or follower 32, for engagement with the cam 25. A spring 33, tends 110

to hold the roller or follower 32 in contact with the cam 25.

The end of the lever 30 opposite the roller 32, is connected by an adjustable link 34, with an outwardly extending arm of the yarn guide 12.

A pin 35 on the lever 30, loosely engaging a slot 36 in the link 34, provides a lost motion connection between the lever and link, 10 allowing for movement of the lever independently of the link and yarn guide 12 when the thrust bar 19 rides on the step or low part of the cam 22 adjacent its trailing end, this step allowing the yarn guide to 15 be lowered gradually into operative position and insuring proper entry of the splicing yarn into engagement with the needles at the beginning of the formation of a high splice heel reinforcement.

20 An adjustable bearing piece 38, fastened in the slot 36 of the link 34, is adapted by engagement with the lever 30, to throw the roller or follower 32, and hold it, out of contact with the cam 25, when the yarn guide 25 12 is lifted and held by the cams 22 and 23 and the thrust bar 19 out of operative position, to prevent unnecessary wear of the follower and cam when the splicing yarn is not being knit into the fabric, as in knitting the 30 toes, legs and heels of stockings.

For shifting the cam 25 axially on the shaft 26, a mutilated ratchet wheel 40 is rotatably mounted on the bracket 27, with its axis at right angles to the shaft 26. The 35 ratchet wheel is intermittently turned to advance the cam 25 to the right, as seen in Figs. 2 and 3, by a feeding pawl 41, pivoted to the upper end of a rocker arm 42, which is pivoted at its lower end to a depending 40 arm on the bracket 27, and is provided between its ends with a roller or follower 43, engaging a side faced cam 44, fixed on the shaft 26. A spring 45 holds the pawl 41 in yielding engagement with the ratchet wheel, and a spring 46 holds the roller or 45 follower 43 in engagement with the cam 44.

A friction drag or brake 47 held by a spring arm 48 in yielding engagement with the ratchet wheel 40, prevents overthrow 50 of the ratchet wheel by the feeding pawl 41.

A cam 49, attached to the ratchet wheel 40, engages a roller or follower 50 on a sleeve or slide 51, guided and movable on a rod 52 carried by the bracket 27 parallel 55 with the shaft 26. The sleeve 51 is provided at one end with a fork arm 53, loosely engaging a grooved collar or reduced neck 54, on one end of the cam 25.

A spring 55 connecting the sleeve 51 with 60 the bracket 27, adjacent the fixed end of the rod 52, tends to shift the sleeve to the left, as seen in Figs. 2 and 3, and holds it in engagement with the cam 49.

A cushion stop 56, adjustably mounted 65 on the rod 52, limits the movement of the

sleeve 51 to the left when it is released by the cam 49 and is retracted by the spring 55 to its initial position.

To automatically stop and start the operation of the splicing mechanism at predetermined points or times, and to determine the length of the reinforcements or the number of courses into which the splicing yarn is knitted, one or more teeth are omitted from the ratchet wheel 40, leaving a blank space 57 in the toothed periphery of the ratchet wheel, so that when the ratchet wheel has made a complete revolution and the blank space is brought opposite the point of the feeding pawl 41, the pawl will work idly in 80 said blank space, and the movement of the ratchet wheel will be arrested.

For starting the splicing mechanism at a predetermined point in the production of a knitted article, a holding and starting pawl 58 is pivoted on the upper end of a lever 59, which is fulcrumed or pivotally mounted on the bracket 27 concentrically with the ratchet wheel 40, and the lower end of said lever is provided with an adjustable pin or 85 spur 60, projecting therefrom into the path of a cam or stud 61 on the pattern drum 17, the cam or stud being so located on the pattern drum that by engagement with the pin or spur 60, it will advance the pawl 58 a 90 sufficient distance to turn the blank space 57 past the point of the feeding pawl 41 and bring the next tooth of the ratchet wheel into operative engagement therewith for advancing the cam 25 to the right, as seen in 100 Figs. 2 and 3, from its initial position. The upper end of the lever 59 is held by a spring 62 normally against a screw or adjustable stop 63, and the pawl 58 prevents reverse or backward movement of the ratchet wheel 105 40. The pawl 58, as shown in Fig. 2, is provided with two or more teeth of sufficient extent to span the blank space 57 on the ratchet wheel 40 and prevent backward movement of the ratchet wheel when the 110 blank space therein reaches the pawl. A spring 64 holds the pawl 58 in yielding engagement with the ratchet wheel.

The cam shaft 26 may be rotated at the same rate of speed as the needle cylinder, by 115 any suitable driving connections, as shown for example, in Figs. 1 and 3, by a gear 65 connecting a pinion 66 on the cam shaft, with a pinion 67 on the main shaft 68 of the knitting machine.

In the operation of the machine, when the thrust bar 19 clears the cam 22 on the pattern drum 17, and the splicing yarn guide 12 is turned down by the spring 15 into operative position on the throat plate 14, the cam or stud 61 on the pattern drum passes the pin or spur 60 on the lever 59, and swings the upper end of the lever to the left away from the stop 63. The pawl 58 being thus advanced, turns the ratchet wheel 120 125 130

40 an interval sufficient to bring the tooth following the blank space 57 into operative engagement with the feeding pawl 41, and the lever is then drawn back by the spring 5 62 into its normal position against the stop 63.

The rocker arm 42 being constantly swung to and fro by the cam 44 and spring 46 during the operation of the machine, intermittently turns the ratchet wheel and the cam 49, which by engagement with the roller or follower 50, advances the sleeve or slide 51 and the cam 25 step by step to the right during the intervals while the follower 32 is traversed by the high part of the cam 25, and the yarn guide 12 is thereby held out of operative position during parts of successive revolutions of the needle cylinder.

The splicing yarn is fed by the yarn guide 20 to the needles during the intervals that the follower 32 rides on the depressed portion 28 of the cam, and is knit with the main 25 yarn into parts of successive courses varying in length according to the position of the cam 25 and the width of the depressed portion thereof traversed by the follower 32.

The shape of the cam 25 and the shape of the cam 49 determine the pattern or outline 30 of the reinforcement produced by the splicing yarn which is knit into parts of variable extent of successive courses. Obviously, as long as the cam 25 is not shifted axially or lengthwise of the shaft 26 but remains in a given position during the splicing operation, the partial successive courses into which the splicing yarn is knit will be of the same length, corresponding with the width of the depressed portion 28 of the cam in the path 35 traversed by the follower 52, and the sides 40 of the reinforcement will be straight and parallel with each other.

By varying the shape of either or both of the cams 25 and 49, the outline of the reinforcements will be correspondingly varied. 45 With cams of the shapes shown by Fig. 2, a tapered reinforcement having inwardly curved side margins of substantially the form shown by Fig. 4, will be produced.

With a cam 25 of the shape shown in Fig. 50 2, reinforcements of various designs having straight or outwardly, inwardly or compound curved side margins, as shown by Figs. 4 to 7 inclusive, may be produced by variation in the shape of the cam 49, which 55 determines the rate and extent of the axial movement of the cam 25.

Variations in the design or contour of the reinforcements are preferably made by changing the shape of the cam 49, which is 60 detachably fastened to the ratchet wheel 40 and can be more readily made than the cam 25.

With each revolution of the cam 25 during the splicing operation, when the follower 32 drops into and bears on the depressed por-

tion 28 of the cam, the yarn guide 12 is released and turned by the spring 15 down into operative position on the throat plate 14, in which position it directs the splicing 70 yarn into the hooks of the needles.

If the cam 49 is shaped, as shown in Fig. 2, to advance the cam 25 slowly at the beginning and more rapidly towards the end of the splicing operation, a reinforcement having inwardly curved sides, as shown in Fig. 4, will be produced. On the other hand, if the cam 49 is shaped to advance the cam 25 more rapidly at the beginning and more slowly towards the end of the splicing operation, a reinforcement having outwardly curved sides, as shown in Fig. 6, will be produced.

At the end of each revolution of the ratchet wheel 40, the blank space 57 in the periphery of the ratchet wheel is brought 85 opposite the point of the pawl 41, and the rotary movement of the ratchet wheel and cam 49 is arrested.

In the present case the splicing mechanism, as shown, being specially designed to 90 produce tapered high heel reinforcements like or similar to that shown in Fig. 4, and also to reinforce the soles of stocking feet with the same splicing yarn, the blank space 57 on the ratchet wheel 40 is located with 95 reference to the cam 49 so that after the high heel reinforcement is completed and while the heel and foot are being knit, the high part of the cam 49 will be held at rest in engagement with the roller 50 on the 100 sleeve or slide 51, and the cam 25 will be held with the wider part of the depression 28 in position to cooperate with the roller 32.

Upon the completion of the high heel reinforcement when the needle cylinder 105 changes from a continuous rotary to a reciprocating movement, the cam 23 on the pattern drum is brought into engagement with the thrust bar 19 and holds the yarn guide 12 out of operative position during 110 the knitting of the heel.

When the heel is finished, and the needle cylinder resumes its continuous rotary movement, the cam 23 clears the thrust bar 19 and the yarn guide is turned down again 115 by the spring 15 into operative position. The splicing yarn being thus directed into the hooks of the needles 2, is knit into the foot of the stocking and forms a sole reinforcement corresponding in width with the 120 lower part of the tapered high heel reinforcement, the cam 49 standing with its high part against the roller 50 and holding the cam 25 with the wider part of the depression 28 in position to cooperate with the 125 roller 32.

As the reinforced foot is finished and the needle cylinder changes again to a reciprocating movement for knitting the toe of a stocking, the advance end of the cam 22 en- 130

gages the thrust bar and lifts the yarn guide 12 out of operative position, in which position it is held by said cam during the knitting of the toe of one stocking and the 5 knitting of the leg of another stocking.

With the knitting of the toe each stocking is finished and another stocking is started, the thrust bar still resting on the cam 22 and the high part of the cam 49 being still in engagement with the roller 50.

At the beginning of the high heel reinforcement of each stocking, the cam or stud 61 on the pattern drum passing the pin or spur 60, actuates the starting pawl 58 and 15 starts the ratchet wheel 40, the intermittent rotary movement of which is continued by the feeding pawl 41, as hereinbefore explained, for another cycle of operations. The high part of the cam 49 is thus turned 20 by the initial movement of the ratchet wheel 40 out of engagement with the roller 50, and the slide 51 with the cam 25 is instantly shifted back to its initial position against the stop 56 by the spring 55. The cam 25 25 is then advanced intermittently to the right as hereinbefore explained, and the cam 22 having cleared the thrust bar 19, another high heel reinforcement is produced.

With the lifting of the yarn guide 12 out 30 of operative position by the cams 22 and 23 and the thrust bar 19, the roller or follower 32 is thrown and held by its connections with the yarn guide, out of contact with the cam 25, as hereinbefore explained.

35 Various modifications in the construction and arrangement of parts of the machine may be made without departure from the principle and scope of the invention as defined in the following claims.

40 I claim:

1. In a knitting machine the combination with a rotary needle cylinder provided with needles and a yarn guide movable into and out of operative position to direct yarn to 45 the needles, of a rotary and axially movable cam for shifting the yarn guide out of operative position, means for rotating the cam

synchronously with the needle cylinder, a cam for shifting the first cam axially, a ratchet wheel connected and rotatable with the second cam, a rocker arm provided with a pawl for rotating the ratchet wheel and second cam, and a third cam for actuating the rocker arm and pawl.

2. In a knitting machine the combination 55 with a rotary needle cylinder provided with needles and a yarn guide movable into and out of operative position to direct yarn to the needles, of a rotary and axially movable yarn-guide-controlling cam, means for rotating said cam synchronously with the needle cylinder, a cam for advancing the first cam axially, a mutilated ratchet wheel connected and rotatable with the second cam, a pawl for turning the ratchet wheel, and 60 a cam for actuating said pawl to turn the ratchet wheel till the blank space therein is brought opposite the point of the pawl.

3. In a knitting machine the combination 70 with a rotary needle cylinder provided with needles, a yarn guide movable into and out of operative position to direct yarn to the needles, and a pattern drum, of a rotary and axially movable yarn-guide-controlling cam, means for rotating said cam synchronously with the needle cylinder, means tending to shift said cam into and to hold it in 75 its initial position, a cam adapted to advance the first cam axially, a mutilated ratchet wheel connected and rotatable with the second cam, a feeding pawl for intermittently turning the ratchet wheel, a cam for actuating said pawl to turn the ratchet wheel till the blank space therein is brought opposite the pawl, a lever provided with a 80 starting pawl engaging the ratchet wheel, and a cam on the pattern drum arranged to actuate said lever and starting pawl and turn the tooth of the ratchet wheel following the blank space therein into engagement 85 with the feeding pawl.

In witness whereof I hereto affix my signature.

HUMPHREY EVANS.
